UNITED STATES PATENT OFFICE

CHARLES H. LITTLE, OF EAST CLEVELAND, OHIO

RULER

Application filed December 18, 1920. Serial No. 431,587.

This invention relates to rulers, such as scales, and straight edges, and is an improvement over the constructions disclosed in my prior patents, Nos. 1,274,291 and 1,274,292, 5 granted July 30, 1918.

In my prior patents I have shown rulers having features of construction designed to impart to the rulers the chief advantages of both wooden and metal rulers, heretofore commonly employed, and at the same time to eliminate certain well-known disadvantages of both types.

In both my prior patents a non-warping ruler body or core was utilized, this being accurately formed, preferably from sheet metal, so that it would be light in weight, and the design was such that it would be sufficiently stiff and rigid for ordinary purposes. To these metal bodies celluloid or 20 pyroxylin coverings were applied either in the form of strips, as disclosed in Patent No. 1,274,291, or in the form of a coating, as disclosed in Patent No. 1,274,292, which coating I proposed to apply from pyroxylin 25 in a substantially liquid state in some suitable way as by a dipping or spraying process.

While the constructions disclosed in my prior patents answer the major portion of 30 the requirements, I have by the present invention effected certain important improvements which pertain both to the covering of the core or ruler body which is adaptable for both scales and straight edges, and also to 35 the core itself.

This covering while preferably entirely encasing or enclosing the ruler body, and in that respect being similar to the coating or covering of the ruler body of my prior Patent No. 1,274,292, is in accordance with the 40 present invention applied as a covering, preferably wholly or partially previously formed, and while the covering of the present improved ruler has the desirable characteristics of the covering or coating of my 45 patent just referred to, it has certain marked additional advantages which will be referred to in the following description.

The invention may be further briefly summarized as consisting in certain novel fea-

tures and characteristics which will be described in the specification and set forth in the appended claims.

In the accompanying sheet of drawings wherein I have shown certain forms or embodiments of my invention, Fig. 1 is a top plan view with parts broken away, of a scale embodying the principal features of the invention; Fig. 2 is a fragmentary longitudinal sectional view of the same; Fig. 3 is a 55 transverse sectional view; Fig. 4 is a fragmentary bottom view; Figs. 5 and 6 are transverse sectional views respectively through the covering and through the metal core or ruler body as they are preferably 60 formed; Fig. 7 is a perspective view of a portion of the scale showing the manner in which the covering is slipped over the core or ruler body; Fig. 8 is an enlarged partial 65 transverse sectional view of the celluloid 70 coverings; Figs. 9, 10 and 11 are transverse 75 sectional views through a straight edge formed in accordance with the invention, these three views showing different embodiments of the invention.

Referring now to the drawings, and first to Figs. 1 to 8, which show my invention applied to a ruler adapted to be provided with graduations, and commonly called a scale, this ruler or scale includes a core or body 10 80 which is non-warping and permanent in the sense that it will retain its shape under ordinary usage, and which has the right degree of stiffness and rigidity. For this purpose I prefer to use a light metal, such as 85 aluminum or a magnesium aluminum alloy which is lighter, stiffer and stronger than aluminum. By the use of a metal of this kind, which is sufficiently light in weight, and has the other necessary requirements, 90 the core can be made solid as herein illustrated. A core of this type can be formed in various ways, such as by a rolling, extruding or drawing process which will produce without machining, a strip or body 95 uniform in cross section at all points of its length, and having straight parallel edges. The extruded or drawn core is peculiarly fitted for this purpose in view of the fact that in the process of forming it, it receives 100

a skin or surface hardening which adds to the stiffness of the core, and is free from bending or internal stresses due to machining.

5 As shown most clearly in Fig. 6, the core 10 has upper and lower faces 10^a and 10^b which are preferably flat and parallel, and beveled marginal portions 10^c which incline downward from the upper face 10^a, substantially but not quite to the lower face 10^b, leaving narrow flat edges of approximately one-sixty-fourth of an inch (more or less) in width. Likewise, the core when it has been cut to the right length for the 15 scale, is provided with tapped openings 10^d to accommodate screws 11 for securing to the scale chuck plates, one of which is shown at 12 in Fig. 1; these chuck plates when employed, adapting the scale for use with a 20 drafting machine, although it is immaterial whether these openings 10^d are provided in the core or body 10, before or after the enclosing covering is applied to the core. This connection to solid metal gives a 25 substantial hold at the end of the ruler which practically does away with any slight motion at this point, this being especially desirable in long rulers or straight edges. It is to be understood also, that the chuck 30 plates, and hence the openings 10^d will be omitted in the event that the scale is to be used as a separate tool, and not in a drafting machine.

After the core or body 10 is formed into 35 the right length, it is encased in a covering 13, which preferably entirely encloses the core, and which is preferably formed of celluloid or some other suitable nitroderivative of cellulose, such as pyroxylin or other suitable substance having certain well-known 40 properties or characteristics of celluloid, i. e. which in its finished state is hard, smooth, easily movable over drafting paper, and will not soil the paper; which is tough in the 45 sense that it will not chip off, and can be flexed without liability of breakage or tearing; which has cohesive properties such that fine smooth lines and characters can be cut therein; which undergoes a shrinkage that 50 will cause the covering to tightly grip the core or body and retain permanently its shape and accuracy; and which for use in producing the straight edges can be made in transparent form, to form the covering and 55 also transparent edges which are very desirable for straight edges. Inasmuch as celluloid has all these properties and characteristics, and others which admirably adapt it for this use, celluloid is the preferred material for this covering. The 60 word "celluloid" is used in the claims as applicable to any material having the above characteristics, or the major portion of them.

65 The covering 13, can perhaps be made to

advantage in different ways, but preferably it is extruded in the form of a tube of the same shape, especially in its interior dimensions as the shape of the core or body 10 and of substantially its size, though as will subsequently appear, the external dimensions of the tube need not, and preferably do not coincide precisely with the external dimensions of the core or body 10. 70

At any rate, when the tube or covering 75 and the core or ruler body are formed in proper lengths for a scale of given length, the tube is slipped over the core, the interior dimensions of the tube being such that when this is done, the tube or covering will fit so tightly onto the core, and everywhere conform to its shape.

Generally at this point in the manufacture of the ruler, the celluloid covering is allowed to "season". By way of explanation 85 of this term, it may be stated that as is well known, celluloid undergoes a constant shrinkage; but the shrinkage is comparatively rapid for a period immediately after the celluloid is formed, due to the rapid initial evaporation of the solvents used in forming the celluloid. This shrinkage, which is the seasoning referred to above, is of considerable importance in the formation of the present improved rulers inasmuch as 90 it causes a very decided or intense gripping or adherence of the sheath or covering to the core, and this is an important factor in the attainment of the high degree of accuracy and permanency which my improved rulers 95 possess. 100

The covering is then completed by the closure of the ends of the tube, preferably by inserting in the ends of the tube up against the ends of the core 10, filler pieces 105 14, rounded at the bottom as shown in Fig. 2, these filler pieces being formed of wood or other material to which celluloid can be effectively cemented, and by cementing the ends of the tubes to these filler pieces and 110 also cementing together the top and bottom walls of the tube. In Fig. 2 the bottom wall of the tube is shown as brought up around the rounded portion of the filler piece 14, and the top wall is brought down 115 and lapped over it as shown at 15. In this manner a very effective seal is obtained which will hold against the shrinkage stresses of the celluloid. I do not regard it essential that these filler pieces 14 be 120 employed, as they may be omitted, especially in some instances as when the core has a comparatively low temperature coefficient, in which event the end portions of the tube can be cemented together to 125 form the end closure and seal, or if desired, other ways of sealing the ends of the tube may be employed.

It is generally the case that the celluloid covering is allowed to shrink or season be- 130

fore the end of the tube is closed, as above explained, but in some instances it may be desirable to close and seal the ends of the tube before this seasoning takes place, in 5 which event the ruler will be subjected to longitudinal shrinkage stresses of the celluloid, whereas by sealing the ends of the tube after the initial shrinkage or seasoning, the stresses are chiefly of a transverse 10 nature.

Then to complete the scale its marginal portions are provided with the cut graduations and characters indicated at 16, these 15 graduations being brought down to the edges of the covering, which edges are square, as will be seen by reference particularly to Fig. 8, as is highly desirable for accurate drafting work.

It might be mentioned at this point that 20 the square edges of the core and of the covering itself are novel important characteristics of the present scale not possessed at least to a sufficiently high degree by the rulers shown in my prior patents, and 25 it should be noted also, that the entire flat ruling edge is formed of celluloid, which is not the case with prior rulers having celluloid strips attached to their marginal portions.

30 Additionally my present ruler with the covering previously formed and applied by the method above explained, while possessing all the advantages of the coating or covering applied uniformly with the 35 pyroxylin or celluloidal substance in a liquid form, as explained in my Patent No. 1,272,292, has important advantages over the coating or covering applied by my former method. In both instances the coverings completely enclose the cores or ruler bodies, and in both instances the non-warping cores hold the coverings in their initial accurate shape, and in both instances the coverings strongly adhere to the cores, 40 though in the present instance the character of the adherence between the covering and the core is of a somewhat different mechanical character than in my prior ruler. In the way of additional advantages, however, 45

50 I might mention that with the covering applied in accordance with the present invention, i. e., previously formed and slipped over the core, not only can a somewhat smoother and thicker covering be obtained, 55 but the covering of the ruler made in accordance with the present invention is more durable and less liable to chip off than the coating or covering of my prior ruler. But a more important advantage lies in the fact 60 that as already intimated, the exterior shape of the covering or sheath need not coincide with the interior shape. That is to say, instead of the covering being uniform in thickness at all points, I may make 65 certain parts thicker than others. For ex-

ample, the beveled portions 13^a may be, and preferably are thicker than the parallel top and bottom portions of the covering, and I am enabled by the present method to provide relatively thick or heavy edge portions 70 13^b, as clearly shown in Fig. 8. This last mentioned feature leaves ample material for planing the celluloid edges to exact straight and parallel lines, either in manufacture, or when the edges have been marred by rough 75 usage. My improved rulers, as herein made, can be produced inexpensively, this latter being an advantage over even the ordinary wooden rulers, especially in view of the fact that the loss in producing the latter 80 is excessive, due to the wastage caused by warping. Finally it might be mentioned that inasmuch as the adherence between the core and covering is of a mechanical 85 nature, it is possible to make the ruler so 90 as to allow for a very slight longitudinal relative movement between the core and covering to compensate for the differences in their temperature coefficients which may be desirable in comparatively long rulers. 95

While a celluloid covering in the form of a seamless extruded tube is now regarded as preferable, I do not wish to be confined to a tube which is seamless, and in the event a seamed tubular covering is employed, I do 95 not wish the invention in its method aspect to be limited to one whose seam is closed prior to the insertion of the core in the sheath.

Though the invention has great utility in 100 the production of rulers of the scale type, it is equally advantageous in the manufacture of rulers of the straight edge type, which are formed in the same manner, and will have the chief structural characteristics of the 105 scales made by this invention, modification being made only in the cross sectional shape of the core and covering. Under the circumstances, simply cross sectional views such as Figs. 9, 10 and 11 are thought to be sufficient 110 to illustrate this adaptation of the invention.

The straight edge has a core or body 17 which may be formed by any of the methods mentioned for the production of the core 10, 115 or otherwise if desirable, but in this instance the core is rectangular in cross section. The core is completely enclosed by a covering 18, consisting preferably of celluloid as in the first instance, and this covering is preferably 120 applied to the core, and will have its ends sealed, preferably precisely like the covering 13 of the scale.

The covering 18 is, however, provided with 125 relatively thick or heavy marginal portions 18^a which in practice will preferably be transparent as with ordinary straight edges which are formed with wood having transparent strips cemented to their edges. But, of course, the main outstanding advantage 130

of straight edges made in accordance with the present invention, over ordinary wooden straight edges and other straight edges having celluloid strips applied to their edges or 5 marginal portions is that with the present construction the celluloid forms a permanent part which cannot be accidentally detached from the core or body, and which is held in its original straight condition against warping 10 or distortion which is such an objectionable characteristic of wooden straight edges. These straight edges thus made, can be made very long, their accuracy and permanency being wholly unaffected by their 15 length.

The covering can, like the covering 13 of the scale, be a seamless extruded tube, but it is not essential that it be seamless, for as illustrated in Fig. 10, the tube could be built 20 up from marginal portions 18^a, and top and bottom strips 18^c, with the parts overlapping and cemented together substantially as illustrated, producing a tube having substantially the strength of an extruded seam- 25 less tube such as shown in Fig. 9.

Other modifications may be made in some of the details as for example, as shown in Fig. 11, wherein the core or straight edge body here designated 17^a has along its marginal edges central outstanding fins or tongues 17^b which fit into correspondingly shaped slots in the marginal portions of the sheath or covering here designated 18^a.

As above stated, the ends of the covering 35 may be, and preferably are closed and sealed precisely as explained in connection with the scale, and although the sheath, like the sheath of the scale, tightly frictionally engages the surface of the core and is held in 40 conformity therewith, with its ruling edges held in straight, parallel lines, however, I do not wish to imply that there may not be a minute relative movement at times between the core and covering, or portions thereof, 45 especially if the ruler or straight edge is formed of unusual length, or if the coefficient of expansion of the core is much in excess of that of the covering.

While I have described the preferred constructions and the preferred ways of carrying out the invention, as well as the preferred materials, it is to be understood that I am not to be confined to any of the precise materials or details of construction here- 55 in illustrated and described, except to the extent that I am limited by the terms of the appended claims, with due regard for equivalency.

Having described my invention, I claim: 60 1. A ruler comprising a metal stiffening core, and a covering, non-metallic of hard, durable, preformed material completely and tightly enveloping the core including its ends and held thereby against substantial 65 movement in any direction.

2. A ruler comprising a formed non-metallic shell having a ruling edge and a drawn metal core in the shell and serving to impart the features of accuracy, permanency and stiffness to the shell, the latter completely 70 and tightly enveloping the core and by the latter being held from movement in all directions.

3. A ruler comprising a metal core, and a covering composed of preformed hard celluloidal material completely and tightly enveloping the core and held by the latter against movement in all directions, said covering being provided with a ruling edge 75 which is maintained straight by the core. 80

4. A ruler comprising a metal core having one or more flat edges, and a formed celluloidal covering completely and tightly enveloping the core and having one or more edge portions of greater thickness than the 85 remainder.

5. A ruler comprising a metal core having a square edge, and a formed celluloidal shell completely and tightly enveloping the core so as to be held thereon against substantial 90 movement in any direction, said shell having a square ruling edge adjacent the square edge of the core.

6. A ruler comprising a non-warping core having a flat edge, and a formed celluloidal covering completely and tightly enveloping the core including its ends and held from substantial movement thereon in any direction, said covering being provided adjacent the flat edge of the core with a thickened edge portion provided with a flat ruling edge. 95

7. A ruler comprising a metal core, a non-metallic shell in the form of a tube enclosing the core and having a ruling edge held straight by the latter, said tube having its ends closed, and non-metallic filler pieces between the ends of the metal core and the ends of the tube. 100

8. A composite ruler consisting of a hard durable shell forming a ruling edge and a stiff non-warping core which the shell completely envelops whereby the shell is held from movement on the core in any direction, the shell and core comprising preformed elements applied and held tightly together. 105

9. A composite ruler comprising a stiff, solid, non-warping, non-wooden core, and a shell completely enclosing the core including its ends and composed of hard preformed celluloidal material, the parts being mechanically held together against movement in any direction and in effect forming a solid piece. 110

10. A composite ruler having top and bottom surfaces extending in parallelism to the outer edges which are transparent, straight and parallel, said ruler being composed of celluloid with a stiffening core therein, the celluloid being relatively thin along the op- 115 120 125 130

posite sides of the core and relatively thick along the edges of the core.

11. A composite ruler composed of celluloid and a non-warping core enclosed by the celluloid, the latter consisting of top and bottom strips and edge strips secured to the first named strips so as to form a unitary celluloidal body with ruling edges held straight by the core.

10 12. A composite ruler composed of celluloid and metal enclosed by the celluloid, the latter comprising strips extending along opposite sides of the metal and strips extending along the edges of the metal between 15 the first named strips and secured to the latter so as to form a solid unitary enclosure.

13. A ruler comprising a metal stiffening core and a covering of hard, durable non-metallic preformed material completely and tightly enveloping the core and held thereby against substantial movement in any direction independent of cementing.

In testimony whereof, I hereunto affix my
25 signature.

CERTIFICATE OF CORRECTION.

Patent No. 1,728,419.

Granted September 17, 1929, to

CHARLES H. LITTLE.

It is hereby certified that error appears in the printed specification of the above numbered patent requiring correction as follows: Page 4, line 60, claim 1, strike out the comma and compound word ", non-metallic", and line 62, before the word "performed" insert the compound word "non-metallic"; and that the said Letters Patent should be read with these corrections therein that the same may conform to the record of the case in the Patent Office.

Signed and sealed this 5th day of November, A. D. 1929.

M. J. Moore,
Acting Commissioner of Patents.

(Seal)
